(57) **CLAIM**

The ornamental design for a storage receptacle as shown and described.

DESCRIPTION

FIG. 1 is a front perspective view of a storage receptacle according to my new design;

FIG. 2 is a rear perspective view thereof;

FIG. 3 is a perspective view thereof, showing the receptacle in an open condition;

FIG. 4 is a front view thereof;

FIG. 5 is a rear side view thereof; and,

FIG. 6 is an end view thereof.

The broken line depictions form no part of the claimed design.
